ARTHUR A. OSWARD, OF EAST ORANGE, NEW JERSEY, ASSIGNOR TO WESTERN ELECTRIC COMPANY, INCORPORATED, OF NEW YORK, N. Y., A CORPORATION OF NEW YORK.

SYSTEM OF ELECTRICAL CONDUCTORS.

Application filed November 14, 1924. Serial No. 749,819.

This invention relates to systems of electrical conductors and more particularly to improvements in elevated conductor systems.

The design of the supporting structure for any antenna system involves both electrical and mechanical effects and in most cases leads to a compromise dictated by economic considerations. When metal supporting towers or poles are used, the proximity of the metal structure to the antenna conductors serves to reduce the effective height of the antenna. Currents flowing between the ground and the antenna by way of the towers or guy wires bear more or less random phase relations to the current in the member or members of the antenna proper, thereby introducing losses and undesired directional effects. These losses and effects become particularly pronounced as the natural period of the towers approaches the period of the radio signal. Placing the towers beyond the intense electrical field of the antenna involves expensive construction due to the mechanical stresses in the supporting structures. When non-conducting supports constructed of materials such as wood, brick or reinforced concrete are used, high dielectric losses are introduced unless the supports are also placed beyond the intense electrical field. Such losses are greatly increased by absorption of moisture during rain or fog. Wet wood poles subject to intense high frequency fields frequently catch fire caused by heating due to dielectric losses.

It is an object of this invention to increase the effective height of an antenna.

Another object is to increase the efficiency of radiation of an antenna.

A further object is to reduce the mechanical and electrical stresses set up in the supporting structures of an elevated aerial.

A feature of the invention relates to means for supporting elevated conductors and for making electrical connections between the conductors and ground.

Another feature relates to means for insulating elevated conductors and for supporting the windings of the loading coils associated therewith.

This invention may be employed in systems of antennae, particularly multiple tuned antennae and it contemplates the provision of means functioning as supporting

structures for the elevated conductors of the antenna and as multiple down leads therefor.

In other words, the metallic supporting towers or poles of an antenna are incorporated into the antenna whereby the currents present therein are caused to radiate useful rather than undesired energy. Certain loading coils required in the multiple down leads of an antenna are so positioned with respect thereto that the voltages generated in the coils may be reduced and their construction simplified. These coils may be conveniently wound upon insulating devices that serve also to electrically separate the elevated conductors from direct contact with the supporting structures.

In the drawings, wherein like reference characters have been used to indicate like parts in the several figures:

Fig. 1 is a plan view illustrating the arrangement of a multiple tuned antenna using the supporting masts as down leads.

Fig. 2 is a view in elevation illustrating a multiple tuned antenna arranged in a manner different from that of Fig. 1.

Fig. 3 is a detailed view in prospective illustrating the method of supporting an antenna and loading coils therefor.

Fig. 4 illustrates a slightly different supporting arrangement for the system of Fig. 3.

The antenna illustrated in Fig. 1 comprises elevated conductors arranged in the form of a triangle and supported by masts or towers 10, 11 and 12 positioned at the apices of the triangle. The elevated conductors are arranged to form cages 13, 14 and 15 suspended between the masts or towers 10, 11 and 12 and cage 16 radiating from the geometric center of the tower system and so connected as to bisect the sides of the triangle formed by the cages 13, 14 and 15. The antenna conductors are attached to the masts 10, 11 and 12 by means of strain insulators 17.

Loading coils 18, 19 and 20 are positioned at or near the top of the towers 10, 11 and 12, respectively, and are connected between the antenna conductors and the masts at the apices of the triangle.

The center of the antenna is connected to ground by a path including the secondary

winding of a transformer 21, the primary winding of which may be connected to any source 22 of electrical waves.

The masts 10, 11 and 12 are connected to ground; for example, as illustrated in Fig. 2, and serve as down leads for the antenna conductors. The antenna is thus divided into a plurality of tuned sections formed by the inductances of the respective portions of the antenna conductors and their capacity to ground. By so utilizing the supporting towers as down leads and by placing the loading coils at the top rather than at the bottom of the towers as has been customary in the past, the effective height of the antenna is increased and the losses which would be otherwise introduced by the currents in the towers are prevented.

Moreover, the construction of the insulators may be simplified since they need not be designed to withstand the maximum voltage between elevated conductors and ground but need only withstand the voltage drop over the loading coil which may be made less than the maximum voltage by positioning the coils so that current antinodes occur at points remote therefrom.

In Fig. 2 the invention is illustrated as applied to a multiple tuned antenna of a type different from that illustrated in Fig. 1. The antenna of Fig. 2 comprises an elevated conductor 23 supported upon masts 24. The conductor 23 is provided with loading coils 25 connected between it and the respective masts. A source of waves 22 is coupled by means of the transformer 21 to the antenna conductor 23. The masts 24 are each connected to ground as illustrated. An auxiliary loading coil 26 is connected between the outer terminal of conductor 23 and ground.

The system shown in this figure functions in the same manner and has the same features and advantages as the system shown in Fig. 1. The masts 24 function as down leads for the elevated conductor 23, whereby other down lead conductors are eliminated and the efficiency of radiation from the antenna is increased by virtue of the absence of detrimental currents that would be present if down leads separate from the supporting structures were employed.

An added advantage of the arrangements illustrated in Figs. 1 and 2 resides in the fact that the construction of the masts is simplified by virtue of the reduction in the mechanical stresses in the system resulting from the elimination of the down leads normally provided which give added weight to the elevated conductors, necessitating increased provision for their support.

In Fig. 3 another method of supporting the elevated conductors of an antenna is illustrated. The conductors 27 are suspended by means of insulators 28 from the cross-arm 65 of a grounded tower 29 and are connected to

the tower 29 through loading coils 30. These coils are wound upon the insulators 28, respectively. By virtue of the fact that the antenna conductors 27 are connected to the mast 29, the voltage between the conductors and mast may be reduced to a small value represented by the drop in voltage in any instance across the coil winding connected therebetween. This results in an advantage in that the dielectric strength of the insulators 28 need not be as great as would otherwise be required and accordingly the design of these insulators is simplified and their cost of construction is reduced.

In Fig. 4 the conductor 27 is shown mounted upon the insulator 28, which in turn is mounted upon the cross-arm 31. The winding of the choke coil 30 is supported upon the insulator 28 as illustrated in Fig. 3. While but one conductor is shown, it is to be understood that the antenna may consist of a plurality of conductors each supported as described above.

Although this invention has been illustrated and described in connection with certain embodiments consisting principally of antenna systems, it is not to be limited by the specific disclosure, but only as indicated by the scope of the appended claims.

What is claimed is:

1. A system of elevated antennæ conductors, means for supporting said conductors, said means being connected to ground, and a loading coil connected between said conductors and said supporting means.
2. A system of elevated antennæ conductors, a grounded supporting means therefor, means for electrically loading said conductors, said loading means being positioned at the top of said supporting means.
3. A system of elevated antennæ conductors, a grounded supporting means therefor, means for electrically loading said conductors, said means being connected between the top of said supporting means and said conductors.
4. A system of elevated conductors, conducting supporting means therefor connected to ground, means for electrically loading said conductors, said means being connected between said supporting means and said conductors and positioned at the top of said supporting means.
5. A system of elevated conductors, grounded supporting means therefor, means for insulating said conductors from said supporting means, and loading inductance for said conductors comprising coils wound upon said insulating means.
6. A system of extended elevated conductors, supporting means therefor attached thereto at separated points, individual loading inductances connected between said conductors and said supporting means, said supporting means being connected to ground.

7. An antenna comprising a plurality of sections of cage type conductors, a plurality of supports for said conductors, said supports being connected to ground, and means for making electrical connection between said supports and said conductors comprising a plurality of loading coils.
8. An antenna which comprises a plurality of tuned sections, means for providing individual return leads to ground for each section, said means acting also to support said antenna, and a loading coil included in each of said return leads.

9. An aerial conductor, a mast for supporting said conductor, said mast comprising conductive material connected to ground, an insulator attached to said mast and to said conductor, and a loading inductance electrically connected to said mast and said conductor, said inductance comprising a conductor wound upon said insulator.

In witness whereof, I hereunto subscribe my name this 11th day of November A. D., 1924.

ARTHUR A. OSWALD.
